UNITED STATES PATENT OFFICE.

WILLIAM B. GRIFFIN, OF GLENS FALLS, NEW YORK.

DESIGN FOR A VEHICLE-BODY.

SPECIFICATION forming part of Design No. 21,453, dated April 12, 1892.

Application filed March 5, 1892. Serial No. 423,954. Term of patent 3½ years.

To all whom it may concern:

Be it known that I, WILLIAM B. GRIFFIN, a citizen of the United States, residing at Glens Falls, in the county of Warren and State of New York, have invented and produced a new and original Design for Vehicle-Bodies, of which the following is a specification, reference being had to the accompanying drawing, forming a part thereof, and which shows 10 a side view of a vehicle, the body being constructed and ornamented in accordance with my design.

The leading feature of my design consists in the representation of a series of rings arranged between the arm and the side of the seat-box; and my design consists, further, in the representation of a basket-work panel set 15 centrally upon the open field of the side of the seat-box.

Referring to the drawing, A represents the side of the vehicle-body, B the seat-box, and C the arm. D represents a series of rings arranged in horizontal alignment beneath the said arm and forming a part thereof. E is the representation of the basket-work panel set 20 centrally upon the open field of the side of the seat-box, and, if desired, a narrow basket-work strip F may be arranged upon the side of the seat-box near the top of the same.

Having thus described my invention, what I claim is—

The design for a vehicle-body, substantially as shown and described.

WILLIAM B. GRIFFIN.
